UNITED STATES PATENT OFFICE.

GEORGE B. COWLES, OF NEW BRITAIN, CONNECTICUT.

MACHINE FOR PUTTING SPRINGS IN LOCK-BOLTS.

SPECIFICATION forming part of Letters Patent No. 283,081, dated August 14, 1883.

Application filed April 19, 1883. (No model.)

To all whom it may concern:

Be it known that I, GEORGE B. COWLES, a citizen of the United States, residing at New Britain, in the county of Hartford and State 5 of Connecticut, have invented certain new and useful Improvements in Machines for Putting Springs in Lock-Bolts, of which the following is a specification.

My invention relates to improvements in 10 machines for putting springs into lock-bolts and lock-tumblers; and the objects of my invention are to do this work automatically when the springs are fed into the machine in the form of a continuous wire, and thereby to do 15 the work not only cheaper but more accurately than by hand. I attain these objects by means of the mechanism illustrated in the accompanying drawings, in which—

Figure 1 is a plan view of my machine. Fig. 20 2 is a rear elevation thereof. Fig. 3 is a detached side elevation and partial section on line *w*, Figs. 1 and 2. Fig. 4 is a like view on line *z*, Figs. 1 and 2. Fig. 5 is a like view on line *y y*, Figs. 1 and 2. Fig. 6 is a like view 25 on line *x x*, Figs. 1 and 2. Fig. 7 is a front elevation of a detached portion of my machine. Fig. 8 is an under side view of a detached part for holding the spring; and Fig. 9 is a plan view of the lock-bolt with spring attached.

So far as I know this work has heretofore 30 been performed by hand only. As shown in the drawings, the machine is adapted for putting springs into lock-bolts, but it may readily be adapted for putting springs into lock-tumblers.

A designates the bed of the machine, upon 35 which is mounted a circular bed or table, B. Upon the surface of this table is an intermittently-revolving disk, C, having mortises *a*, 40 which are designed to receive and hold the lock-bolt D, Fig. 9. Said disk constitutes a carrier-plate and moves over the stationary bed. This disk is driven by means of ratchet-wheel *b* and pawl *c*, mounted upon an oscillating pawl-carrier, *d*, operated by means of lever *D'* and cam *E* upon the main shaft *F*, whereby an oscillating motion is imparted to the pawl-carrier *d* sufficient to drive the pawl back over one tooth of the ratchet-wheel *b*, and upon 45 its next movement to impart to said ratchet and disk C one-tenth of a revolution. This disk is mounted with sufficient friction in its

bearings to cause it to stop in the position in which it is left by the pawl, and so retain it in that position until the next advance movement of said pawl.

The spring *e*, Fig. 9, of the lock-bolt is fed into the machine in the form of a continuous wire, *f*, Fig. 1, where it first passes into the feeding mechanism *g*, which is operated first 55 by a lifting-cam, *G*, to depress the forward end of the lever *H* and grip the wire, and then by a side cam, *I*, to move the forward end of the lever *H* sidewise and feed the wire *f* forward a given distance. So soon as this 60 forward movement of the wire takes place the cam *J* on main shaft *F* operates to lift the lever *K* to force the holder *h* down upon the wire *f*, and hold it in that position while the feeding mechanism *g* retreats, ready for another forward movement. Figs. 5 and 6 show 65 side elevations of these levers *K* and *H*, together with the feeding mechanism and holder *h*; but these parts are not new with me, and have been applied heretofore in other machines for feeding wire a given length at a 70 time. The wire *f* passes from the holder *h* through the cut-off *i*, with its end extending between the holding-jaws *k*, Figs. 3 and 8, at which time the end of the wire projects over 75 the edge of the disk *C* and under the end of the lever *L*, and is directly over one of the mortises *a* in said disk. This cut-off *i* is formed in the end of a slotted plug, *r*, which extends from in front of the holder *h* to the end of the 80 block *R*. Said block is made adjustable by means of slot *s* and screw *t*, Fig. 1, so as to 85 adjust the block, the cut-off *i*, and shear-lever *N* to or from the carrier-plate, to provide for cutting off different lengths of springs. The 90 slot in this plug *r* is tapering, and is about the depth of the wire *f* at its front end, (see Fig. 5,) and about twice the depth of the wire at the cut-off end, (see Fig. 4,) so as to allow the wire to be depressed before it is cut off. The 95 cam *O* then operates to depress the forward end of lever *L*, and also to depress the spring-plate *l*, having the holding-jaws *k*, and drive the spring edgewise into the slot designed to receive it in the lock-bolt *D*, the mortises *a* in 100 the carrier plate or disk *C* having been previously filled with lock-bolts by the operator. The wire will spring edgewise in the tapering slot of the plug enough to admit of its being

thus driven edgewise before it is cut off. The cam M upon the main shaft F then throws the shear-lever N upward and forward to cut off the wire, as shown most clearly in Fig. 4. At 5 the next intermittent movement of the disk C another lock-bolt is brought under the spring-plate l, the wire is again fed forward, another length is cut off, and the lever L is again depressed to force another spring into a lock-bolt, as before. The opening m is made through 10 the bed of the machine and in the edge of the circular table B, and immediately over said opening is a knock-out, P, mounted on the end of lever L, so that when said lever is depressed this knock-out strikes the lock-bolt and pushes it down through the mortise m, 15 when it falls from the machine.

The spring-gage n extends around over the disk C and in front of the spring-plate l to hold 20 the lock-bolt down as the front end of lever K ascends. The spring-plate l, Fig. 8, is made thin for the greater portion of its length between its two ends, so that it may be depressed by the end of lever L and then returned again 25 to its normal position. The mortises a in the carrier-plate or disk C are so formed relatively to the position of the spring-plate l and its holding-jaws k that when the carrier stops with a lock-bolt under said plate l the jaws k 30 will be a little to one side of a position over the edge of the lock-bolt, as indicated by broken lines in Fig. 9. The flat face e, Fig. 9, of said spring-plate l will at that time be directly over the slot in the lock-bolt designed to receive 35 said end, so as to press it firmly into place under the action of lever L and cam O.

I have herein specified an intermittently-revolving disk for carrying the lock-bolt under the device for inserting the springs; but it is 40 evident that other carriers may be substituted therefor—as, for instance, a straight carriage moving from front to rear and stopping underneath the spring-driving mechanism, when the other parts of the machine will operate

substantially the same as before. The springs 45 are intended to fit the slot in the lock-bolt so closely that simply pressing them into place will suitably fasten them therein.

I claim as my invention—

1. The combination of a carrier for holding 50 and moving the lock-bolt or tumbler, mechanism for feeding the wire, pressing the spring-wire into said lock-bolt or tumbler, and cutting it off, substantially as described, and for the purpose specified. 55

2. The combination of a stationary bed or table having opening or mortise m, an intermittently-moving carriage having holding-mortises, mechanism for feeding the spring-wire, for driving it into the lock-bolt or tumbler, for cutting it off, and a knock-out for 60 discharging the bolts from the mortises in the carrier, substantially as described, and for the purpose specified.

3. The combination of an intermittently- 65 moving carriage and its operating mechanism, the spring-plate l, having holding-jaws k, depressing-lever L, and its operating mechanism, substantially as described, and for the purpose specified.

4. The combination of an intermittently- 70 moving carrier, holding-jaws for holding the springs over the carrier, and mechanism for depressing the spring and driving it edgewise when thus held within the jaws, substantially 75 as described, and for the purpose specified.

5. The combination of an intermittently- 80 moving carrier, mechanism for driving the spring edgewise into the lock-bolt or tumbler, cutting-off mechanism, and means for adjusting the cutting-off mechanism to and from the carrier, substantially as described, and for the purpose specified. 70

GEORGE B. COWLES.
